UNITED STATES PATENT OFFICE.

WILLIAM CARRICK, OF BOSTON, MASSACHUSETTS.

RIBBON OR LABEL HOLDER FOR HATS.

SPECIFICATION forming part of Letters Patent No. 278,877, dated June 5, 1883.

Application filed March 22, 1883. (No model.)

To all whom it may concern:

Be it known that I, WILLIAM CARRICK, of Boston, in the county of Suffolk and State of Massachusetts, have invented certain Improvements in Ribbon or Label Holders for Hats, of which the following is a specification.

This invention has for its object to provide a convenient device for securing to the inside of a hat a ribbon or label having the owner's name or initials. Such ribbons have generally been stitched to the lining of the hat; but owing to the shape of the hat it is a somewhat difficult operation to stitch the ribbon so that it will lie smoothly in the hat.

15 My invention consists in a resilient frame or clamping-plate adapted to secure itself to the interior of a hat and to clamp the embroidered ribbon against the crown of the hat, said frame or plate being constructed to show the lettering on the ribbon.

20 Of the accompanying drawings, forming a part of this specification, Figure 1 represents a view of the under side of a hat having my improved ribbon-holder. Fig. 2 represents a section on line *x x*, Fig. 1. Fig. 3 represents an enlarged sectional view of one end of the holder and a portion of the hat. Fig. 4 represents a side view of one end of the plate or holder. Fig. 5 represents a modification.

25 The same letters of reference indicate the same parts in all the figures.

In the drawings, *a* represents a hat, and *b* the usual ribbon, having the name or initials of the owner.

30 *c* represents my improved device or holder for securing the ribbon *b* to the hat. Said device is a resilient plate or frame, of sheet metal or other suitable material, long enough to extend across the interior of the crown of the hat and bear at its ends against the sides thereof, behind the sweat-band *g*. The ends of the holder are preferably provided with points or teeth *c'*, adapted to penetrate slightly the body of the hat, as shown clearly in Fig. 3, and thus 35 secure the holder to the hat in an arched position.

To secure the ribbon to the hat the ribbon is laid in place in the hat, and the holder *c* is then placed against the ribbon and engaged at 40 its ends with the sides of the hat-body. The holder is nearly straight when in its normal

shape. Consequently when placed in the hat it is sprung from its normal shape, and its own resilience causes its ends to press against the sides of the hat-body and its central part 55 to press against the crown of the hat, and thus firmly secure the ribbon. The holder has an opening of sufficient size to expose the letters on the ribbon, as shown in Fig. 1. The width of the holder is preferably about the same as 60 that of the ribbon.

If desired, the holder may be adjustable in width, in which case it should be made of two parallel strips or side pieces connected by extensible cross-strips. Instead of a frame or 65 plate constructed as described, two strips or side pieces may be employed, entirely detached from each other, each holding one edge of the ribbon and engaged with the hat at its ends.

I do not limit myself in all cases to providing the holder with points *c'* at its ends. The holder may be of sufficient length to bear at 70 its ends on the lower portion of the sweat-band and be supported by the latter.

My improved holder may be applied to flat-crowned hats as well as to those of the form 75 shown in Fig. 2.

A modification is shown in Fig. 5, in which the holder is composed of four arms pointed at their ends and adapted to engage with the 80 hat-body, like the examples above described. This form of holder, instead of clamping the ribbon against the crown or lining of the hat, would usually be secured to the back of the ribbon by stitches, or otherwise, and placed next 85 the crown or lining, so that it would be covered, or mainly so, by the ribbon. I do not therefore limit myself to the holder to clamp the ribbon against the crown. The last-described form is adapted for a large ribbon or 90 piece of material with a monogram.

I am aware that the lining of a hat has been provided with a pocket sewed to the lining and open at one end to receive a card. My improved holder, however, is not secured to 95 the lining of the hat, but is engaged at its ends with the sides of the hat-body, and is pressed by its own resilience against the crown of the hat, or the lining thereof.

I claim—

1. A hat ribbon or label holder composed of a resilient strip or plate adapted to be en-

gaged at its ends with the sides of a hat-body, and to be pressed by its own resilience against the crown thereof, as set forth.

2. A hat ribbon or label holder composed of 5 a resilient plate, strip, or frame having hooks or points at its ends, adapted to be pressed into the sides of the hat-body by the resilience of the plate.

In testimony whereof I have signed my name to this specification, in the presence of two subscribing witnesses, this 20th day of March, 1883.

WILLIAM CARRICK.
